BURGLAR SIGNAL ALARM FOR SAFES

Original Filed Oct. 15, 1925

UNITED STATES PATENT OFFICE

JOSEPH KEREKES, OF DETROIT, MICHIGAN

BURGLAR SIGNAL ALARM FOR SAFES

Application filed October 15, 1925, Serial No. 62,503. Renewed May 31, 1930.

This invention relates generally to alarms for safes and the like, the invention having more particular reference to a novel type of switch therefor. The invention has for an object the provision of an improved device which will sound an alarm when a safe is opened or tampered with. A further object of the invention is to provide a device of this nature which will also sound an alarm in 10 event an attempt should be made to move the safe.

For further comprehension of the invention, and of the objects and advantages thereof, reference will be had to the following description and accompanying drawing and to the appended claim in which the various novel features of the invention are more particularly set forth.

Fig. 1 of the drawing is a side sectional view of my improved safe.

Fig. 2 is a front elevational view.

Fig. 3 is a sectional view taken on the line 3—3 of Fig. 1.

Fig. 4 is an enlarged sectional detail view 25 of my improved plunger switch.

Fig. 5 is a sectional view taken on the line 5—5 of Fig. 4.

Fig. 6 is a sectional view taken on the line 6—6 of Fig. 4.

Fig. 7 is a sectional view taken on the line 7—7 of Fig. 4.

Fig. 8 is a diagrammatic view of the electrical system.

As here embodied a safe 10 is shown with 35 a layer 11 of any suitable insulating material placed between the inner wall 12 and the outer wall 13 of the said safe 10. The said outer wall 13 of the safe 10 is connected by means of an insulated wire 14 to a horn 15 of any similar device, the inner wall 12 of the safe 10 being connected to a switch 16 of the locked type by means of an insulated wire 17 and to the battery 18 of suitable capacity or any suitable source of electricity, by means of the insulated wire 19, the said insulated wires 17 and 19 being connected to the said switch 16 so as to disengage with the said switch 16 when the door 20 of the safe 10 is opened. The heretobefore mentioned construction and wiring is

such as will cause the horn 15 to be sounded when the electrical circuit between the inner wall 12 and the outer wall 13 is completed by means of a drill or any instrument which would pierce the walls.

My improved plunger switch 21 is attached to the bracket 22 and is wired so that by means of a completed circuit across the terminals 23 and 24 suitably located on the closed end 28 of the hollow cylinder 27, by means of the circuit breaker 25 the horn 15 will be sounded.

My improved plunger switch 26 identical in design and construction to the heretofore mentioned plunger switch 21 is attached as will be hereinafter described, and is wired so that by means of a completed circuit across the terminals 44 and 45 by means of the circuit breaker 29 the horn 15 will be sounded as described in connection with the heretobefore mentioned plunger switch 21.

Referring in particular to Fig. 4 of the accompanying drawing, in which I have shown an enlarged cross sectional detail view of my improved plunger switch as shown and referred to by the heretobefore mentioned numerals 21 and 26. This device comprises a hollow cylinder 27 having one of its ends closed as designated by the numeral 28, a

slidable piston 29 or cylindrical disc is attached to the operating rod 30 having one end protruding through a suitable aperture in the said closed end 28 of the hollow cylinder and attached at that end the heretobefore mentioned circuit breaker as designated by the said numerals 25 and 29, the other end of the operating rod protruding through a suitable aperture in the rotatable disc 30 and also in the cover 31, and so mounted as to be a slid fit in the apertures, the coil spring 32 being placed over the operating rod 30 between the closed end 28 of the hollow cylinder 27 and the piston 29.

Referring also to Figures 5 and 6, the cover 31 is attached to the open end of the hollow cylinder 27 by means of a plurality of screws 33 or any suitable device so as to allow the said rotatable disc 30 to be placed under the said cover 31 and so located as to be easily rotated or turned by means of the

handle 34 or conveniently located lever protruding through a suitably located slot 35 in the said cover 31; the heretobefore mentioned construction being such as will permit a plurality of apertures 36 conveniently and suitably located in the said cover 31, to coincide with a plurality of similar apertures 37 in the said rotatable disc 30 by means of the said handle 34, a leaf spring 38 being placed between the said handle 34 and the cover 31 and having its extremities extending in suitably located indentures 39 so located as to hold the rotatable disc 30 in any desired position.

15 My improved plunger switch as designated by the numeral 21 attached to the said bracket 22 by means of slots 41 in the said bracket 22 to slidably accommodate the protruding portion 40 of the said hollow cylinder 27, the slots 41 extending lengthwise of the bracket 22, the hollow cylinder 27 having a suitably located lug 42 with a threaded aperture to accommodate the hand screw 43, so that the plunger switch may be attached in any desired position on the bracket 22, the bracket 22 being attached at any desired location on the inner wall 12, so that the operating rod 30 will make contact with the inner side of the door 20 of the safe 10, as shown in Figures 1, 3 and 4 of the accompanying drawing. In event the safe door is opened, the coil spring 32 will cause the circuit breaker 25 to complete the circuit and the horn 15 will be sounded, by means of the handle 34 of the rotatable disc 30 the timing of the closing of the plunger switch 21 may be determined, as the plurality of apertures 36 and 37 may only partly coincide, in which event it would take a longer time interval for the air between the piston 29 and the rotatable disc 30 to be expelled, were the plurality of apertures 36 and 37 coincidental; consequently the action of completing the said circuit would be slower. A slow action as here described would permit any one such as a bank official familiar with the location of the plunger switch 21, to open the safe door and stop the completing of the said circuit so that the said horn 15 would not be sounded. It should be understood that the same results could be obtained by attaching the plunger switch 21 on the bracket 22 at a relative close position to the door 20.

55 Referring in particular to my improved plunger switch as designated by the heretobefore mentioned numerals 26, as heretobefore stated the plunger switch 26 is identical in design and construction to the heretobefore mentioned plunger switch 21 but is attached to any part of the building so that the said operating rod 30 will make contact with any part of the outer surface of the said safe 10, preferably the bottom of one of the legs 41 as shown in Figures 1 and 2 of the 65 accompanying drawing, so that in event the

safe is moved the coil spring 32 will cause the circuit breaker 29 to complete the circuit and the horn will be sounded.

Having described my improved safe and my improved plunger switch fully its use and manipulation is obvious. It should be understood that my improved device may be made of any suitable materials such as used in devices of this nature.

75 While I have above described the preferred form, construction and arrangement of the several elements employed, it will be understood that the device is nevertheless, susceptible of considerable modification therein, and I therefore reserve the privilege of resorting to all such changes as may be fairly embodied within the spirit and scope of the invention as claimed.

80 Having thus described my invention, what I claim as new, and desire to protect by Letters Patent of the United States is as follows:—

85 In a cylinder and piston type circuit closer, a means for retarding the piston motion, comprising a cover having a base portion and a flange portion, the flange portion being attached to the end of the cylinder, providing a space between the end of the cylinder and the base portion, a disc rotatively mounted in the space, the flange portion of the cover 90 being formed with a slot, a handle attached to the disc and projecting from the slot, the base portion of the cover being formed with a plurality of apertures, the disc being formed with a plurality of apertures align- 95 able with the apertures of the base portion in one position of the disc, the handle being movable to turn the disc to disalign the said apertures, and a leaf spring attached to the handle, the ends thereof engaging against the flange portion so as to hold the rotatable disc 100 in adjusted positions, to adjust the rate of retardation of the piston.

105 In testimony whereof I have affixed my signature.

110 JOSEPH KEREKES.
